CABLE SHEATH CUTTING TOOL

Kenneth T. Miller, Longmeadow, Mass.

Application November 4, 1958, Serial No. 771,909

4 Claims. (Cl. 30—91)

This invention relates to improvements in tools and is directed more particularly to a cutting tool for cutting a metal sheath of armored cable such as a metal sheath of BX cable or BX sheath.

The principal object of the invention is directed to the provision of a hand tool for cutting the sheath of BX cable to facilitate the ready and easy separation of sections thereof.

BX cable as is well known, is an armored cable, and includes one or more insulated wires within a metal sheath. Said sheath is formed by a helically wound metal strip having one edge of the convolutions thereof overlapping and interlocked with the underlying edge of adjacent convolutions. The BX sheath alone may be used as a conduit in wiring installations, and when in place, wire may be snaked therethrough.

The metal strip forming the BX sheath or conduit is of relatively hard steel. The cross section of the strip is generally in the shape of an S for interlocking purposes, and when arranged as a helix, it is extremely difficult to cut.

Tools in the form of hack-saws or cutting pliers are well known for cutting BX sheath but same have not been altogether satisfactory.

Such tools require considerable physical effort and time in cutting, the ends of the separated sheath sections cut thereby are ragged and sharp, and there is a likelihood of cutting or impairing the wires carried therein in the cutting operation.

According to the novel features of the invention, a tool is provided, which is of small size, and is easily and readily operable to cut through the sheath in one operation for separating the sections thereof.

As one special feature of the invention, the tool embodies a cutting blade which cuts longitudinally of the BX and entirely across a convolution of the metal strip to enable sections of the BX to be separated.

The tool is so constructed that little physical effort is required to provide the force necessary in cutting the strip of the sheath.

As another feature of the invention, the tool embodies means for clamping the BX for a cutting operation in such a way that, a cutting blade acts to cut across and through the strip of the sheath so that it is completely and cleanly severed.

As a further feature of the invention, a cutting blade is operated in such manner as to obviate the likelihood of cutting or injuring the wire or wires within the sheath. Such is accomplished by an elongated blade which has a sharpened end which, in a cutting operation, operates in a plane spaced from and parallel to a plane extending through the longitudinal axis of the BX. Thereby, the cutting edge is directed non-radially of the BX rather than radially so as not to contact wires within the BX.

Various changes and modifications may be made within the spirit and scope of the invention, to be hereinafter shown and described, in its presently preferred form.

In the drawings:

Fig. 1 is an elevational view of a cutting tool embodying the novel features of the invention, with the clamp plate thereof in its open position;

2

Fig. 2 is an end elevational view of the tool shown in Fig. 1, with the clamp plate thereof in clamping position;

Fig. 3 is an elevational view of the rear side of the main plate of the tool;

Fig. 4 is an edge view of the clamp plate of the tool;

Fig. 5 is an edge view of the cutting blade of the tool shown in relation to a circle representing the cross section of a strip of BX;

Fig. 6 is an elevational view of a length of BX and showing the cut made in the sheath by the tool; and

Fig. 7 is an elevational view of a section of the BX, shown in Fig. 6, which has been removed following a cutting operation.

Referring now to the drawings more in detail, the novel features of the invention will be fully described.

It will be understood that reference to BX will mean the sheath of BX, whether or not a wire or wires are enclosed within the sheath, and it envisions a sheath without wires for use as a conduit for same.

20 A main plate is shown at 2 which has an upper extension 4. A clamp plate 6 is hingedly connected to the lower edge thereof by means such as leaves 8 and 10 of a hinge 12, shown as secured to the plates 2 and 6 respectively as by screws 14 or the like. The hinge parts may be formed on the plates 2 and 6, if desired.

The plates 2 and 6 are provided with elongated semi-circular grooves 16 and 18 respectively. These are arranged to provide an elongated clamping guideway for the BX when the clamp 6 plate is in the upper clamping position, as shown in Fig. 2.

25 A clamp screw 20 has an inner end in a slot 22 of the upper side of the plate 2. A pivot pin 24, on which the screw is pivoted, threadedly engages the plate 2 inwardly of the slot 22, as shown. A thumb nut 26 is provided on the screw 20.

30 As the clamp plate 6 is swung to clamping position, as in Fig. 2, the screw is swung so as to lie in a notch 28 of the clamp plate 6. The guideway is formed to receive BX of a certain diameter, and when in the guideway, the thumb nut 26 is turned on the clamp screw 20 to act on the clamp plate 6 so as to clamp the BX in the guideway between the plates 2 and 6.

35 A cutting blade 30 has a lower end portion reciprocable in a guideway 32, and is provided with a lower sharpened cutting edge 34. Said blade may be provided with any form of cutting means desired.

40 As shown in Fig. 6, an outer or bead edge 38 of the sheath forming metal strip, in each convolution, overlies, so as to interlock with, an opposite inner outwardly turned edge 40. Each convolution may be said to include a bead 38, and a valley 42, the latter being disposed between adjacent beads 38.

45 The cutting blade 30, in a cutting movement thereof, reciprocates in a plane which is spaced from, and in parallelism with, a plane extending through the longitudinal axis of the guideway and BX therein. In Fig. 5, the longitudinal vertical edge of the cutting blade 30 is shown, and is related to a line 44 representing a plane through the longitudinal axis of the guideway and BX therein, which BX is represented by dash lines 46.

50 Such positioning of the cutting blade insures that the wires in the sheath will not be cut, as would be the case were the blade operable radially of the longitudinal axis of the guideway.

55 The cutting edge 34 of the cutting blade is of such width and is so arranged that, in the cutting operation, the bead portion 38 and opposite edge portions of a convolution are cut through, as at 44 in Fig. 6. In order to cut the convolution all the way across, the next convolution is cut as at 46, but one convolution is entirely severed.

60 With the convolution so severed the section 48 of BX is turned counterclockwise relative to section 50 so as to become separated therefrom, as in Fig. 7.

To cut the BX strip at the desired location, means is provided for positioning the BX relative to the cutting blade. Such means includes a pin 54 extending through a slot 56 in the groove 16 of plate 2 which is carried by a leaf spring 58 secured to the rear side of plate 2, see Fig. 3.

The BX is placed in the groove 16 of plate 2 with the pin 54 in a valley 42 of the BX whereby a convolution to be cut is positioned correctly relative to the cutting edge of the blade 30.

The cutting blade 30 is moved downwardly for a cutting operation by a screw 60 having a head 62 rotatable in a T slot of the blade 30. Said screw 60 threadedly engages the extension 4 of plate 2.

A stop nut 66 is secured in adjusted position on the screw 60 by a set screw 68. The nut abuts the extension 4 to arrest downward movement of the blade so that the cutting edge of the blade will pierce the sheath only sufficiently to cut through a convolution.

The upper edge of the blade 30 abuts the underside 70 of the extension 4 in its upper fully retracted position.

The clamp plate 6 cannot be swung to its upper clamping position unless the blade 30 is in its fully retracted position, as in Fig. 1. Nor can the clamp plate 6 be swung away from its BX clamping position, unless the blade is fully retracted.

A safety member 72 is secured to the outer edge 6' of clamp plate 6 by screws 74 or the like. Said member has a projecting nose 76 on the outer end thereof, see Fig. 4. The cutting blade 30 is provided with a complementary notch 76 in a side thereof, see Fig. 1.

With the blade 30 in the fully retracted position of Fig. 1, the member 72 of the clamp plate 2 will pass through the notch 76 of the blade as the clamp plate 6 is swung to its clamping position. Unless the blade 30 is in the position shown, the member 72 of plate 6 will abut the blade, and the notch will not be in the proper aligned position.

With the clamp plate 6 in its clamping position, same cannot be swung away therefrom unless the blade is in its retracted position, as the nose 76 of member 72 will abut the rear side of the blade 30.

Various changes and modifications may be made in the form of the tool without departing from the spirit and scope of the invention, and it is desired to secure by Letters Patent of the United States the invention set forth in the appended claims.

I claim:

1. A device for cutting a sheath forming strip of BX comprising, a main plate, a clamp plate hinged to said main plate and being swingable between non-clamping position and BX clamping position relative to said main plate, said plates being provided with longitudinal co-operating grooves providing a BX clamping guideway in the clamping position of said clamp plate, means for moving said clamp plate towards said main plate in the clamping position thereof, said main plate being provided with an elongated blade guide opening into the clamping guideway and extending in a direction transversely relative to the longitudinal axis of the guideway, a blade being reciprocable in the blade guide between retracted and cutting positions and having a cutting edge in the cutting position thereof for cutting BX in the clamping guideway longitudinally and transversely of the convolutions thereof, means limiting reciprocation of said blade to cutting position thereof, and means limiting reciprocation of said blade to retracted position thereof, said blade guide being disposed for reciprocation of said blade in a plane spaced outwardly of and parallel to a plane extending through the longitudinal axis of the clamping guideway.

2. A device for cutting a sheath forming strip of BX comprising, a main plate, a clamp plate hinged to said main plate and swingable between non-clamping position

and BX clamping position on said main plate, said plates being provided with longitudinal co-operating grooves providing a BX clamping guideway in clamping position of said clamp plate, means for moving said clamp plate towards said main plate in clamping position thereof, said main plate being provided with an elongated blade guide opening into the groove thereof extending in a direction transversely relative to the longitudinal axis of the BX clamping guideway, a blade reciprocable in the blade guide between retracted and cutting positions and having a cutting edge in the cutting position thereof for cutting BX in the BX clamping guideway longitudinally thereof and transversely of the convolutions of the BX, means limiting reciprocation of said blade to cutting position thereof, means limiting reciprocation of said blade to retracted position thereof, the blade guide being disposed for reciprocation of said blade in a plane spaced outwardly of and parallel to a plane extending through the longitudinal axis of said clamping guideway, and means preventing positioning of said clamp plate in clamping position when said blade is in other than the fully retracted position.

3. A device for cutting a sheath forming strip of BX comprising, a main plate, a clamp plate hinged to said main plate swingable between non-clamping position and BX clamping position on said main plate, said plates being provided with longitudinal co-operating grooves providing a BX clamping guideway in clamping position of said clamp plate, means for moving said clamp plate towards said main plate in clamping position thereof, said main plate being provided with an elongated blade guide opening into the groove thereof and extending in a direction transversely relative to the longitudinal axis of said BX clamping guideway, a blade reciprocable in the blade guide between retracted and cutting positions and having a cutting edge in cutting position thereof to cut BX in the BX clamping guideway longitudinally thereof and transversely of the convolutions of the BX, means limiting reciprocation of said blade to cutting position thereof, means limiting reciprocation of said blade to retracted position thereof, the blade guide being disposed for reciprocation of said blade in a plane spaced outwardly of and parallel to a plane extending through the longitudinal axis of the BX clamping guideway, and means preventing swinging of said clamp plate from clamping position when said blade is in other than fully retracted position.

4. A device for cutting a sheath forming strip of BX comprising, a main plate, a clamp plate hinged to said main plate and being swingable between non-clamping position and BX clamping position on said main plate, said plates being provided with longitudinal co-operating grooves providing a BX clamping guideway in clamping position of said clamp plate, means for moving said clamp plate towards said main plate in clamping position thereof, said main plate being provided with an elongated blade guide opening into the groove thereof extending in a direction transversely relative to the longitudinal axis of the BX clamping guideway, a blade reciprocable in the blade guide between retracted and cutting positions and having a cutting edge in cutting position thereof to cut BX in the BX clamping guideway longitudinally thereof and transversely of the convolutions of the BX, means limiting reciprocation of said blade to cutting position thereof, means limiting reciprocation of said blade to retracted position thereof, the blade guide being disposed for reciprocation of said blade in a plane spaced outwardly of and parallel to a plane extending through the longitudinal axis of the BX clamping guideway, and means preventing positioning of said clamp plate in clamping position and preventing swinging of said clamp plate away from clamping position when said blade is in other than fully retracted position.
